PINTLE CONTROL MECHANISM FOR
REVOLVING DOORSThurloe M. Hagenbook, Evansville, Ind., assignor
to International Door Company, Evansville,
Ind., a corporation of Illinois

Application January 15, 1937, Serial No. 120,818

11 Claims. (Cl. 20—18)

My invention relates broadly to revolving doors and more particularly to a construction of control mechanism for the pintle of a revolving door.

One of the objects of my invention is to provide a construction of control mechanism for the pintle of a revolving door structure by which the pintle may be readily retracted or projected for allowing the collapsing of the revolving door wings adjacent one side of the revolving door drum or the journaling of the revolving door in operative position centrally of the revolving door drum.

Another object of my invention is to provide a selectively operative spring actuated latch device for maintaining the pintle of a revolving door in retracted or projected position.

A further object of my invention is to provide a two-position shiftable control mechanism for the pintle of a revolving door adapted to receive an insertable key device engageable with the control mechanism for disengaging a spring actuated latch and allowing the pintle to be shifted to either retracted or projected position.

Still another object of my invention is to provide a construction of spring actuated latch carried by the pintle control mechanism of a revolving door and engageable from the housing of the revolving door shaft for permitting the retraction or projection of the pintle.

Other and further objects of my invention reside in the construction of pintle control mechanism for revolving doors as set forth more fully in the specification hereinafter following by reference to the accompanying drawing in which:

Figure 1 is a fragmentary vertical sectional view showing the pintle control mechanism shifted to a position projecting the pintle for supporting the revolving door wings in rotating position; Fig. 2 is an enlarged vertical sectional view taken on line 2—2 of Fig. 3 and showing the external plate of the control mechanism in front elevation; Fig. 3 is an enlarged fragmentary vertical sectional view through the control mechanism with the pintle illustrated in projected position preparatory to an unlatching operation and raising of the pintle; Fig. 4 is a fragmentary vertical sectional view of the pintle control mechanism showing the latching device in operation and the pintle shifted from a projected position to a retracted position and about to be latched in the retracted position; Fig. 5 is an enlarged cross sectional view illustrating the latching device in latched position maintaining the pintle control mechanism in retracted position; Fig. 6 is a transverse sectional view through the pintle control mechanism on line 6—6 of Fig.

3; Fig. 7 is a transverse sectional view on line 7—7 of Fig. 3; Fig. 8 is a transverse sectional view through the control mechanism on line 8—8 of Fig. 3; Fig. 9 is a transverse sectional view through the control mechanism on line 9—9 of Fig. 3, but showing the insertable key in top elevation; and Fig. 10 is a cross sectional view on line 10—10 of Fig. 3 and illustrating the latched device in top elevation engaged in the lower recess of the central tubular shaft for maintaining the pintle in projected position.

Referring to the drawing in more detail, the revolving door wings are represented by reference character 1. A cylindrical housing 2 extends over the central tubular shaft 3, through which the central shaft 4 extends. The pintle 5 is coupled to central shaft 4. Pintle 5 carries at its lower end, a headed portion 6 which is diametrically slotted as indicated at 7 for engaging the diametrically extending member 8 in the seat 9 mounted centrally of the base of the drum of the revolving door. The seat 9 is suitably arranged with respect to the foundation 11 constituting the base of the revolving door drum by means of the journal box 10.

The lower end of the central tubular shaft 3 carries a concentric bushing 12 mounted in cylindrical recess 14 in the tubular shaft 3. There is a longitudinal slot 15 in the tubular shaft 3 in a position intermediate the revolving door hangers, which, for the purpose of simplicity I have not illustrated. The cylindrical housing 2 is provided with a longitudinally extending slot 16 which is aligned with the longitudinal slot 15 in tubular shaft 3.

A block member 17 having a width which readily allows the block member 17 to pass through slot 15 in tubular shaft 3 is secured to central shaft 4 by means of screws 20. The block member 17 is provided with a laterally extending portion 18 from which lugs 21 extend forwardly at opposite ends of the block member 17. There is an intermediate recess 19 in block member 17 between the forwardly projecting lugs 21.

An escutcheon plate 22, conforming to the cylindrical contour of the cylindrical housing 2, is connected by means of screws 23 to the forwardly projecting lugs 21 on block member 17, so that the plate is movable with block member 17. The longitudinal and transverse dimensions of escutcheon plate 22 are such that the longitudinally extending slot 16 in cylindrical housing 2 is always completely covered in either of the limiting positions to which the pintle 5 may be shifted.

The block member 17 is transversely apertured

for the passage of the shank 25 of latch device 24. There is a transversely extending socket 26 in central shaft 4 directly aligned with the aperture in block member 17 through which the shank 25 of latch device 24 extends. A spring 27 is mounted in socket 26 and tends to continuously urge the latch device to a projected position so that the head of the latch device tends to engage either the lower recess 28 in cylindrical housing 2 or the upper recess 29 in cylindrical housing 2 when the block member 17 is shifted to positions in which pintle 5 is either retracted or projected.

In order to effect retraction or projection of pintle 5, I provide a key device 30 having a head or grip 31 thereon and which is adapted to be inserted through the aperture 35 in escutcheon plate 22 and through the passage 33 in block member 17 and through the transversely aligned passage 32 in central shaft 4. The head or grip 31 of the insertable key 30 is of such diameter that it may readily pass through aperture 35 in escutcheon plate 22 and slot 16 in the cylindrical housing 2 and be pressed inwardly for engaging the disc like head of latch device 24. By pressing inwardly on head 31 the disc like head of latch 24 may be moved out of engagement with lower recess 28 in cylindrical housing 2, illustrated in Fig. 3, by movement of the disc like head of latch device 24 against the yielding action of spring 27. When the disc like head of latch device 24 is pressed inwardly out of engagement with the lower recess 28, the head or finger grip 31 may be lifted and the control mechanism shifted vertically from the position illustrated in Fig. 3 to the position illustrated in Fig. 4. By this operation pintle 5 is retracted so that the revolving door wings may be shifted in collapsed relation against one wall of the revolving door drum. The key may be maintained in position by elevating the pintle until the upper limit of the pintle to retracted position is reached, as illustrated in Fig. 4 whereupon the key may be withdrawn, allowing the disc like head of latch device 24 to be forced by means of spring 26 to a seat in the upper recess 29 in cylindrical housing 2. The pintle will then be retained in retracted position by positive engagement between the disc like head of latch device 24 in the upper recess 29 in cylindrical housing 2. The key is so constructed that the shoulder 31a thereof immediately beneath the head 31 serves as an engagement means for a peripheral portion of the disc like head of the latch device 24 for effecting transverse displacement of the disc like head against the action of spring 27.

When it is desired to restore pintle 5 to projected position, the key is again inserted through aperture 33 in block member 17 and through transverse passage 32 in shaft 4 and pressed transversely, allowing shoulder 31a of the head 31 to engage a peripheral portion of the disc shaped head of latch device 24, for moving the latch device transversely against the action of spring 27 and disengaging the disc like head 24 from upper recess 29, allowing central shaft 4 to be moved downwardly and pintle 5 projected in a position for journaling the revolving door wings centrally of the revolving door drum.

In order to prevent accidental jamming of the key device in inserted position, I provide apertures 36 and 37 in the cylindrical housing 2 and respectively aligned apertures 34' and 34 in the central tubular shaft 3 to permit the insertion of a suitable tool for dislodging the key from inserted position should it become impractical to

withdraw the key from the grip or finger portion 31 thereof.

I have found the construction of my invention highly practical in construction and operation, but I realize that modifications of my invention may be made and I desire that it be understood that no limitations upon my invention are intended other than may be imposed by the scope of the appended claims.

What I claim as new and desire to secure by Letters Patent of the United States is as follows:

1. Pintle control mechanism for a revolving door comprising in combination with a central tubular shaft, a housing concentrically disposed about the shaft, said shaft and said housing having aligned longitudinal slots, a projectable and retractable pintle controllable through the central tubular shaft, a member connected with the pintle and having a portion thereof projecting through the slots in the central tubular shaft and the housing disposed about the central tubular shaft and operable through substantially the full length thereof, and latch mechanism carried by said member and engageable with enlarged portions of the slot in said housing in either of the limits of movement of said member for maintaining the pintle in either a projected or retracted position.

2. Pintle control mechanism for revolving doors comprising in combination with the central shaft of a revolving door, a pintle connected with the central shaft, a housing disposed in spaced relation to said shaft and having a longitudinal slot therein, a control mechanism operable through said slot and substantially throughout the full length thereof for vertically shifting the pintle to either a retracted or a projected position with respect to the housing, and means carried by the control mechanism and engageable with enlarged portions of the slot in the housing for maintaining the pintle in either a projected or a retracted position.

3. Pintle control mechanism for revolving doors comprising in combination with the central shaft of a revolving door, a pintle connected with the central shaft, a housing disposed in spaced relation to said shaft and having a longitudinal slot therein, a control mechanism operable through said slot for vertically shifting the pintle to either a retracted or a projected position with respect to the housing and having lugs extending into the slot in said housing, a spring actuated latch carried by said control mechanism and operative to engage enlarged portions of the slot in said housing in either the retracted or projected position of the pintle, and a plate member mounted on said lugs and adapted to cover said slot.

4. Pintle control mechanism for revolving doors comprising in combination with the central shaft of a revolving door, a pintle connected with the central shaft, a housing disposed in spaced relation to said shaft and having a longitudinal slot therein, a control mechanism operable through said slot for vertically shifting the pintle to either a retracted or a projected position with respect to the housing and having lugs extending into the slot in said housing, a spring actuated transversely movable latch carried by said control mechanism, a head on said latch, the slot in said housing having recesses therein corresponding to the retracted and the projected positions of the pintle for receiving the head of the latch and maintaining the pintle in either retracted or projected position, and a plate member mounted on

said lugs and adapted to cover said slot, said plate member having an opening therein embracing at least a portion of the head on said latch.

5. Pintle control mechanism for revolving doors comprising in combination with the central shaft of a revolving door, a pintle connected with the central shaft, a housing disposed in spaced relation to said shaft and having a longitudinal slot therein, a control mechanism operable through 10 said slot for vertically shifting the pintle to either a retracted or a projected position with respect to the housing, a transversely shiftable latch carried by said control mechanism, a head on said latch, the slot in said housing having recesses 15 therein corresponding to the retracted and projected position of the pintle, spring means urging said latch to projected position for engaging the head of the latch in the said recesses, and a key insertable through said slot and engageable in 20 said control mechanism and with the head of the latch for disengaging the head of the latch from either of the said recesses for shifting the pintle from one limiting position to another.

6. Pintle control mechanism for revolving doors comprising in combination with the central shaft of a revolving door, a pintle connected with the central shaft, a housing disposed in spaced relation to said shaft and having a longitudinal slot therein, a control mechanism operable through said slot for vertically shifting the pintle to either a retracted or a projected position with respect to the housing, a latch carried by said control mechanism, a spring operating to yieldably force said latch radially outward, the 35 slot in said housing having recesses therein corresponding to the retracted and the projected position of the pintle, a head on said latch engageable in said recesses in either of the limiting positions of the pintle, and an insertable key 40 transversely directed with respect to the central shaft and through the slot in said housing into said control mechanism, said key having a shoulder thereon engageable with the head of the latch for shifting the latch against the yieldable force 45 of the spring for removing the head of the latch from either of the recesses during the movement of the pintle from one limiting position to the other.

7. Pintle control mechanism for revolving doors as set forth in claim 6 and wherein said central shaft and said housing are apertured respectively in alignment with the positions of said key corresponding to retracted and projected po-

sitions of said pintle, for permitting entry of a tool for ejecting said key with the pintle in either of said positions.

8. Pintle control mechanism for revolving doors comprising in combination with a central 5 tubular shaft and a housing therefor, a retractile and projectable pintle concentrically disposed with respect to said shaft, a block member connected with said pintle, said housing having a slot therein and said block member disposed in said slot, 10 a plate member mounted on said block member and adapted to cover said slot, and means for shifting said block member in said slot for retracting or projecting said pintle.

9. Pintle control mechanism for revolving 15 doors as set forth in claim 8 and including means for latching said pintle in retracted or projected position.

10. Pintle control mechanism for revolving doors comprising in combination with a central 20 tubular shaft and a housing therefor, a retractile and projectable pintle concentrically disposed with respect to said shaft, a block member connected with said pintle, said housing having a slot therein and said block member disposed in 25 said slot, a plate member mounted on said block member and adapted to cover said slot, latching means mounted in said block member and engageable with a coacting portion of said housing, said plate member having an opening therein exposing at least a portion of said latching means, 30 and means for shifting said block member in said slot.

11. Pintle control mechanism for revolving doors comprising in combination with a central 35 tubular shaft and a housing therefor, a retractile and projectable pintle concentrically disposed with respect to said shaft, a block member connected with said pintle, said housing having a slot therein and said block member disposed in 40 said slot, a plate member mounted on said block member and adapted to cover said slot, latching means mounted in said block member and engageable with a coacting portion of said housing, said plate member having an opening therein 45 exposing at least a portion of said latching means, and means insertable through the opening in said plate member and engageable with the exposed portion of said latching means for releasing said latching means and shifting said block member 50 in said slot.

THURLOE M. HAGENBOOK.
